UNITED STATES PATENT OFFICE.

HENRY JOSEPH GRIESHABER, OF CHICAGO, ILLINOIS.

CIGAR LIGHTER AND STAND.

Application filed October 27, 1924. Serial No. 746,813.

To all whom it may concern:

Be it known that I, HENRY JOSEPH GRIESHABER, a citizen of the United States, residing at Chicago, in the county of Cook and State of Illinois, have invented new and useful Improvements in a Cigar Lighter and Stand, of which the following is a full, clear, and exact description, such as will enable others skilled in the art to make and use the same.

My present invention relates to cigar or cigarette lighters and more particularly to that type of lighters in which an electric current is employed to render a small coil incandescent so that the tip of the cigar or cigarette may be readily lighted by placing the same in contact with said incandescent coil.

One of the principal objects of my invention resides in the provision of a lighter of this character that is operated by a gravity-controlled make and brake or switch structure, and the same is so arranged that the incandescent coil is mounted in a suitable holder with conductors leading therefrom to a remote source of current supply. Another object is to provide a structure of this character that does not rely upon the action or recoil of a spring for the purpose of retrieving the holder to its normal position, and which is so constructed and arranged that the current is normally shut off and the coil is inactive when the device is not in use so that the liability fire hazard so often present in devices of this character is thereby eliminated.

Further objects reside in providing a lighter that is extremely simple in construction, dependable in operation, is fabricated from a few parts, and which is novel and sturdy in the arrangement of its several elements. I prefer to carry out my invention and accomplish the before-mentioned objects in substantially the manner herein-after fully described and as more particularly pointed out in the claims, reference being now had to the accompanying drawings that form a part of this specification.

In the drawings:

Figure 1 is a substantially central vertical section of my improved lighter and stand.

Figure 2, is a similar view of the upper and lower portion of Figure 1 in a plane at a right angle thereto and enlarged.

Figure 3, is a transverse section on line 3-3 of Figure 2.

Figure 4, is a vertical section on line 4-4 of Figure 3.

The accompanying drawings are in a sense merely diagrammatic for the purpose of illustrating the principles of my invention and they show a typical or preferred form of the lighter and stand. The same reference characters have been utilized to designate similar parts wherever they occur throughout the several views, and by referring to Figure 1 it will be seen that the stand preferably comprises a suitable base 10 from the central portion of which arises a column or standard 11, that is hollow and which is preferably formed from a metal tube that may be rectangular, circular or other shape in cross-section and is open at the opposite ends. Upon the upper end portion of this column or standard 11, is mounted a plate that is preferably dished out upon its upper face as seen to provide a tray 12, into which ashes, matches and the like may be deposited and which may if desired be provided with holders upon which lighted cigars or cigarettes may be conveniently placed in the usual manner of an ash tray.

Suitable insulation strips 13 are secured to opposite portions of the walls of the column or standard 11, and are so positioned upon the interior of the latter that said strips face each other and are elongated so that they extend from the top of the standard to adjacent the bottom thereof. Each of these strips is provided with a longitudinally disposed groove 14 in its surface that faces the other strip and into these grooves are fitted the guides or tracks 15, that are preferably of metal of high electrical conductivity so that a current may be readily conducted therethrough when desired. Like the strips 13 these electrical conductor tracks do not extend to the bottom of the column or standard but terminate at the end of said strips and above the bottom of the column, and continuing from the lower ends of said strips 13 are short insulation strips 16 that are preferably formed with longitudinal ribs 17 that form non-conducting continuations of the metal tracks 15. The current may be supplied to the conductor tracks 15 from any suitable source by means of wires 18 that pass through an insulating bushing 19 fitted radially into the base 10 of the stand and said wires are then led up alongside each short strip 16 and are con-

nected at their ends in any suitable manner to the metal conductor tracks 15, preferably by binding posts 20. After this assembly has been made the lower open end of the column or standard is closed by a block 21 of insulation material so as to thereby reduce liability of a fire hazard.

The element from which the person operating the device may light a cigar or cigarette may be any of the well known structures for this purpose, and for convenience I have illustrated an element which includes a lava block 22 upon the exposed outer face of which is mounted a spiral coil 23 of low resistance that is readily rendered incandescent by the current flowing therethrough.

The lighter element is housed in a suitable hollow holder 24 having a conical shaped lower end that is centrally apertured for the passage therethrough of an insulated conductor cord 25 the adjacent ends of the wires of which are suitably connected with the respective ends of the coil 23. The holder 24 has an outwardly flared upper portion 26 in order to permit it to rest or seat upon the upper bell-shaped lip of an insulation bushing 27 that fits into a centrally disposed aperture in a plate 28, which latter is removably secured to the tray 12 so as to close the upper end of the column or standard 11.

The cord 25 is long enough to extend to adjacent the bottom of the column or standard where it is secured to and supports a weighted carrier that provides a switch and contact member which maintains the cord taut and has sliding engagement with the tracks within the column or standard so that it may be moved longitudinally therein whenever the holder and lighter unit are raised off the bushing 27 to use the lighter. The switch and contact member just mentioned comprises a metal block 29 of lead or other metal that is provided with a transverse channel 30 and is bored longitudinally at its upper end as at 31 to receive the adjacent end portion of the cord 25. Block 29 is of somewhat rectangular shape as will be seen in the drawings, and intermediate its longitudinal sides it is reduced in thickness to provide marginal rims 32 along its longitudinal edges between which are depressed areas into which are fitted relatively thin insulation pieces 33. Plates 34 also of insulation material are next positioned in these depressed areas between the rims and the several elements are then secured together by tie-bolts or screws 35. These plates 34 each have upper and lower embossments or lugs 36 that project outwardly therefrom in opposite directions that are provided with alining grooves 37 in which the tracks are disposed when the weighted contact member is mounted within the column or standard. These grooves permit the contact

member to be slid up and down longitudinally upon the tracks whenever the lighter unit is removed from or replaced upon its seat and due to the fact that the contact member is much heavier than the lighter unit upon the opposite end of the cord 25 it will retrieve the cord and unit and return it automatically to its seat as soon as the person operating the lighter has finished using it. In order to form the circuit for operating the lighter unit, I have provided spring contacts 38 preferably of brass or the like that extend outwardly from the insulation plates 34 far enough to yieldingly engage with the tracks. These spring contacts 38 are bent laterally intermediate their ends so as to pass through transverse slots 39 in the plates 34 intermediate the groove embossments, and they are then disposed between the backs of the plates 34 and the contiguous faces of the insulation pieces 33 so that their upper ends project into the transverse channel 30 where they are suitably connected with the adjacent ends of the respective wire conductors of the cord 25.

In its normal position of rest the weighted carrier or contact member will be at the bottom of the hollow column or standard 11 in which position the spring contacts 38 will be in engagement with the non-conductor ribs 17 of the short insulation strips 16 and the grooved embossments 36 will likewise be engaged with said ribs 17 so that no portion of the weighted member will be capable of forming an electrical connection. When however the holder of the lighter unit is lifted off its seat, the cord 25 will be drawn upwardly thereby pulling up the weighted member so that after a short travel the spring contacts 38 will come into engagement with the metal conductor tracks 15 which immediately permits the current to flow through the wire conductors in the cord 25 up and through the coil 23 which rapidly heats and becomes incandescent so that the operator may place the tip of a cigar or cigarette against the same and light the article he is to smoke. When finished lighting the article the holder for the unit is returned to its seat which permits the weighted member to gravitate to the bottom of the column or standard drawing back the cord 25 taut and moving the contacts 38 out of engagement with the conductor tracks 15 and thus breaking the circuit.

While I have herein illustrated and described certain specific instrumentalities for carrying out my invention I do not desire to be limited thereto in my claims as changes and modifications may be made without departing from the principles involved. Therefore I wish it understood that all such changes and modifications are fully con-

templated as coming within the scope of my invention as expressed in the appended claims.

What I claim is:

5. A device of the kind described comprising a base, a hollow standard arising therefrom, tracks of non-conducting material mounted at the lower portion of the interior of said standard, tracks of conducting metal continuing from said first tracks to the upper portion of said standard, a weighted carrier slidably mounted on said tracks, yieldable contact members mounted on said carrier and engaged with said tracks, 75 a plate upon the upper end of said standard and provided with an aperture registering with said standard, a holder removably seated in said aperture, a resistance element mounted in said holder, conductors leading 80 from a source of current to said metal tracks, and conductors connecting said resistance element to said yieldable contact members, said carrier being normally positioned at the lower portion of said standard 85 whereby said contact members are engaged with said non-conducting tracks.
2. A device of the kind described comprising a base, a plurality of tracks extending upwardly therefrom, said tracks having non-conductor portions adjacent said base, and a gravity returnable lighter unit having electrical connection with said tracks whereby the raising of said unit will form a circuit through said tracks and the return of 25 said unit will break the circuit through connection with the non-conductor portions of said tracks.
3. A device of the kind described comprising a base, a plurality of tracks extending upwardly therefrom and having non-conductor portions adjacent said base, a gravity returnable carrier movable on said tracks, contacts extending from said carrier into engagement with said tracks, a lighter unit, flexible means providing electrical connection between said unit and contacts, and electric conductors connected with said tracks above the non-conductor portions 35 thereof, whereby the raising of said carrier will form the circuit through said lighter unit and the return of said carrier to its normal position will break the circuit by positioning said contacts in engagement with the non-conductor portions of said tracks.
4. A device of the kind described comprising a base, a plurality of tracks extending upwardly therefrom the portions thereof adjacent said base being of non-conducting material and the remaining portions formed of conducting material, a carrier movable longitudinally upon said tracks and normally engaged with the non-conducting portions thereof, conductors connected 50 with the conducting portions of said tracks, yielding contacts mounted on said carrier and engaged with said tracks, a lighter unit, and a flexible conductor cord electrically connecting said unit and said contacts whereby the movement of said lighter unit will move said carrier to positions in which said contacts will be engaged with the conductor and non-conductor portions of said tracks to make and break the circuit to said lighter unit.
5. A device of the kind described comprising a base, a hollow standard arising therefrom, tracks of non-conducting material mounted at the lower portion of the interior of said standard, tracks of conducting metal continuing from said first tracks to the upper portion of said standard, a weighted carrier slidably mounted on said tracks, yieldable contact members mounted on said carrier and engaged with said tracks, 75 a plate upon the upper end of said standard and provided with an aperture registering with said standard, a holder removably seated in said aperture, a resistance element mounted in said holder, conductors leading 80 from a source of current to said metal tracks, and conductors connecting said resistance element to said yieldable contact members, said carrier being normally positioned at the lower portion of said standard 85 whereby said contact members are engaged with said non-conducting tracks.
6. A device of the kind described comprising a lighter unit, flexible conductors leading therefrom, a support, a plurality of conducting and non-conducting elements mounted on said support, and a gravity-returnable slide connected with said flexible conductors and movable longitudinally with respect to said support to positions to engage 90 respectively said conducting and non-conducting elements whereby to make and break the circuit to said lighter unit.
7. A device of the kind described comprising a hollow standard, flexible conductors disposed therein and adapted to be partially withdrawn therefrom during the operation of the device, a lighter unit connected to the upper end of said conductors, a weight normally maintaining said conductors taut within said standard, feed wires leading into said standard, and means interposed between said conductors and feed wires for forming a circuit through the former when said unit is raised and for 100 breaking the circuit when said unit is returned to normal position.
8. A device of the kind described comprising a hollow standard, a seat upon the upper end thereof, an automatically returnable lighter unit removably mounted on said seat, flexible conductors extending longitudinally of said standard and adapted to be partially withdrawn therefrom during the operation of the device, a gravity-actuated element normally maintaining said conductors taut within said standard, feed wires leading into said standard, and means interposed between said conductors and feed wires for forming a circuit through the former when said unit is raised from its seat for 110 breaking the circuit when said unit is returned to its seat.
9. A device of the kind described comprising a hollow standard, a seat at the upper end 120

thereof, a lighter unit removably mounted on said seat; flexible conductors connected to said unit and extending longitudinally into said standard, gravity means normally maintaining said conductors taut, feed wires leading into said standard, and means for electrically connecting said feed wires and said conductors to make and break the cir-

cuit through said lighter unit when said unit is respectively raised from and replaced upon said seat.

Signed at Chicago, county of Cook and State of Illinois, this 23rd day of October, 1924.

HENRY JOSEPH GRIESHABER.
